PIPE REAMING AND BURRING ATTACHMENT FOR STOCK AND DIE IMPLEMENTS

Thomas A. Caliendo, South Ozone Park, N. Y.

Application December 16, 1948, Serial No. 65,656

1 Claim. (Cl. 77—73)

1 This invention relates to reamers, and in particular to a type adapted to be mounted in association with a pipe threading stock and die.

A particular object of the invention is to provide a reamer that is mounted in a holder so that the reamer tool can be easily and quickly adjusted to the end of the pipe being threaded and one that is tensioned to provide the necessary reaming pressure as the threading dies advance with respect to the end of the pipe being threaded.

Further objects of my invention include a mounting for a reamer that provides for an initial adjustment of the reamer to cutting position with a minimum of time and effort and thereafter further pressure adjustment of varying nature depending upon the hardness of the pipe metal; to provide a thread operated adjusting means for initially positioning the reamer and yieldable cushioning means that may be varied in yielding force to suit the operating conditions, and to provide a tool in which the reamer may be directly adjusted through the use of an adjustable slide member that coacts with yielding means to maintain a desired reaming pressure on the parts.

With these and other objects in view, the invention comprises certain constructions herein-after described and then particularly pointed out in the claim, and a preferred embodiment of my invention is illustrated in the accompanying drawing, in which:

Figure 1 is a view in side elevation, parts being shown in section, of a reamer attachment to be used in association with a pipe or tube threading tool;

Figure 2 is a section on the line 2—2 of Figure 1, showing the adjustable connection between the reamer tool and the holder;

Figure 3 is a view in side elevation of the reamer attachment showing an adjusted position of the tool;

Figure 4 is a view similar to Figure 3 showing a position of the parts when the reamer is under a maximum working tension;

Figure 5 is a view in side elevation, a part being illustrated in section, showing a modified form of the invention; and

Figure 6 is a section on the line 6—6 of Figure 5 showing the association of the adjustable parts of the holder and reamer.

Referring to the drawing in detail, 10 indicates the threading dies of a conventional stock and die threading tool 11 used, for instance, in cutting a thread on the end of a pipe 12 from

10 the inside open end of the latter of which it is desired to remove the burr left in the cutting operation, and to smoothen the end of the pipe by reaming a finishing bevel therein. It is usual to mount the reamer device directly on the dies 10 and to this end, I employ a holder frame 13 comprising a ring or annular section 14 having laterally extending wings or tabs 15 and vertically disposed posts 16 shaped to provide vertical guide ribs 17 on the inner surfaces thereof. The upper ends of the posts are bridged by a yoke 18 seating in recessed upper extremities of the posts and detachably secured thereto by the screws 19. The holder is secured to the dies by machine screws 21 and can be readily detached therefrom, the tabs 15 being suitably slotted to permit adjustment of the cutting dies.

20 The reaming or burring cutter 20 is of the conventional conically fluted type and is adapted to the holder with a minimum amount of change. It is centrally recessed in the upper end to provide a bore 22 in which is fixed, in any suitable manner, the lower end of a threaded spindle 23 which, in turn, operates in the internally threaded bore 24 of an adjusting sleeve 25. The latter, as well as the spindle and the reamer, are arranged concentrically with respect to each other and axially of the holder. The sleeve is 30 threaded at its upper end as at 26 and passes freely through a hole 27 in the yoke 18, the hole being concentric with a seat 27A formed in the under side of the yoke to provide a bearing surface for a spring 28 encircling the sleeve and bearing at its opposite end against a collar 29 abutting the lower end of said sleeve. The bore 22 opens into a cavity 30 in the reamer into which the sleeve 25 extends to raise the former to maximum position as shown in Figure 1. Through the use of the cavity the holder may be of minimum length while permitting maximum adjustment of the reamer to fit different sizes of pipe. The threaded end 26 of the adjusting sleeve or rod above the yoke has fixed thereto as by a set-screw 31, a thumb nut 32 through the medium of which the sleeve may be manually rotated to raise and lower the reamer by the retraction or projection, respectively, of the spindle 23. In Figure 3, the reamer is in cutting position with respect to the end of the pipe with the spindle partly projected. The spring 28 will yield as the reamer revolves. In order to increase the tension, operation of the thumb screw to further project the spindle will 45 place the spring under greater tension and, as

a result, the reamer will be under greater pressure against the pipe. At Figure 4, the maximum position of completely closed spring indicates a limit which probably would not occur as a general thing in regular use, but the operation of the thumb screw to any position between those shown in Figs. 3 and 4 results in a variation of the spring tension.

The reamer has diametrically opposite flutes milled out to afford a sliding fit of the reamer along the guide ribs 17, the teeth 33 adjacent said flutes being flattened in their upper reaches as at 34 to fit between the posts 16 of the holder frame. By removing the yoke, the reaming cutter can be quickly removed for sharpening or replacement.

In the form of the invention shown in Fig. 5, the frame 35 comprises posts 36 having inner ribs 37 for guiding the vertical adjustment of the reamer 38 as the latter is forced down by a spring 39 acting between an upper seat 40 in a yoke 41 and a cavity 42 in the upper end of the reamer 38. The spring is tensioned by adjustment of the yoke 41 which is channelled as at 43 to have sliding fit over the posts 36 and slotted as at 44 to allow passage of screws 45 through which the yoke is held in any adjusted position or completely removed. The reamer has secured axially thereof a rod 46, the upper threaded end 47 of which carries a thumb nut 48 so that the reamer can be raised or lowered as will be understood. The frame 35 has the same shape in its base portion as does the frame of device 13 and is adapted for attachment in like manner to the dies of a stock and die tool.

It is evident, therefore, that I have provided a combination reaming and burring tool that can be readily used in connection with a stock and die and will ream out the rough end of a pipe as the threading operation takes place.

My invention is not to be restricted to the precise details of construction shown since various changes and modifications may be made therein without departing from the scope of the invention or sacrificing the advantages to be derived from its use.

What I claim is:

A reamer adapted to be mounted on a pipe threading implement for burring the open end of the pipe during a threading operation comprising a frame, including a yoke portion, means for demountably securing the frame to the implement, a cutter having a recess in the top face thereof, a threaded spindle secured in the recess and extending upwardly out of said cutter, a sleeve threaded over said spindle and projecting upwardly through a hole in the frame the lower end of the sleeve being shaped to provide a collar and the upper end being externally threaded, a thumb nut on said upper threaded end above said frame, means for securing the nut to the sleeve whereby the latter can be moved axially of the spindle to raise and lower the cutter and to vary the work engaging pressure thereof, and coacting means on the cutter and on the frame for preventing turning movement of the cutter relatively to the frame.
